UNITED STATES PATENT OFFICE.

ETHEL M. QUIRK, OF PHILADELPHIA, PENNSYLVANIA.

BREAST-SUPPORTER.

1,237,095.

Specification of Letters Patent. Patented Aug. 14, 1917.

Application filed January 25, 1917. Serial No. 144,490.

To all whom it may concern:

Be it known that I, ETHEL M. QUIRK, a citizen of the United States, residing at Philadelphia, county of Philadelphia, and 5 State of Pennsylvania, have invented a certain new and useful Improved Breast-Supporter, of which the following is a specification.

The present invention relates to a breast 10 supporter designed to be worn so that corsets are unnecessary and is particularly adapted for theatrical use although the same is capable of other uses.

Considerable difficulty has been experienced by the theatrical profession in procuring a form of breast supporter which answers the particular requirements of the calling. Broadly stated, two forms of supporters are now used, two wit:—brassières 15 which are worn in connection with corsets and serve to bind and compress the bust and bust supporters constructed of metal, elastic and non-elastic fabric or combinations thereof and equipped with numerous 20 buckles, fastening mediums, bands, straps, belts and other devices calculated to render said supporter unsatisfactory and commercially unvaluable for the desired purposes herein specified.

30 The principal object of the present invention is to overcome the above recited disadvantageous features and provide a bust supporter intended to be worn so that corsets are unnecessary and adapted to raise 35 the feminine breast, counteract the tendency thereof to droop and support the same in an easy and comfortable position so as to definitely conform the figure to natural youthful lines and to establish both as to 40 appearance and actual conditions natural, easy and graceful body symmetry. A further object of the present invention is to provide a bust supporter so designed that it operates to hold the breast in a natural 45 and firm condition in contradistinction from permitting agitating or unnatural moving thereof calculated to result from acrobatic or like dancing. A further object of the 50 present invention is to provide a bust supporter which in addition to possessing the above described advantages is calculated to permit of utmost freedom of certain organs and muscles of the body. A still further object of the present invention is to provide 55 a bust supporter constructed of inelastic fabric as linen and free of unsightly, pro-

truding attachments so that the same may be readily worn under evening and like gowns of extremely thin material. A still further object of the present invention is 60 to provide a breast supporter of the character stated which requires no special steps in its manufacture or expensive fabric in its construction and which may therefore be economically manufactured and sold at 65 relatively low cost.

With these and other objects in view the invention consists of the improvements hereinafter described and finally claimed.

The nature, characteristic features and 70 scope of the invention will be more fully understood from the following description taken in connection with the accompanying drawings forming part hereof and in which:

Figure 1 is a perspective view of a bust 75 supporter embodying features of the invention.

Fig. 2 is a developed plan view illustrating the inner face of the breast supporter.

Fig. 3 is a perspective view illustrating 80 the practical application of the breast supporter, and

Fig. 4 is a fragmentary view of a slightly modified form hereinafter referred to.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

The supporter of the present invention is designed principally for use by the theatrical profession, for instance, by acrobatic and other dancers, although the supporter 100 of the invention may, with equally satisfactory results, be worn generally and particularly with décolleté gowns. In the drawings the bust supporter is shown as comprising an article of wearing apparel resembling somewhat a brassière although structurally and in use, it differs materially therefrom. In practice, the supporter is manufactured of inelastic fabric, preferably linen, and a multiplicity of pieces or sections of such material are used in the make up thereof. As each side of the supporter is a duplicate in

so far as general construction is concerned, a description will be given of only one side thereof after first describing the formation of the central closed front portion thereof.

5 The vertical edges of the two pieces that join in the center of the supporter between the substantially conical pockets for the busts are designated 10 and are cut upon the bias and joined as by stitching to form a 10 pliable rib 12. The straight of the material is thus caused to extend rearwardly toward and lies beneath the central horizontal line of the bust. The section 10 extends from the rib 12 to the vertical central bust line.

15 The top edge of such section 10 is slightly curved and the bottom edge is cut upon the bias. The adjoining section 13 is so disposed that the straight of the material extends from the vertical central bust line to 20 a point adjacent an armpit portion, said section 13 being connected to section 10 as by stitching as at 14. That edge of section 13 which extends from the central bust line to the underarm portion is slightly curved 25 upwardly. The bottom edge, the underarm portion and the outer edge thereof are all cut upon the bias. Joining these two sections 10—13 as by stitching 15 is a tapered tab section 16. The straight of the material 30 of this tab is in a direction upwardly from the center of the supporter toward a shoulder strap. The lower edge of section 16 which is attached to tops of sections 10—13 is downward curved as shown. The back 35 section 18 which is joined to section 13 as by stitching 19 is straight along the top edge thereof and straight at its outer edge. The bottom edge is cut upon the bias as shown. Extending beneath and connected 40 to the sections 10—13—18 is a lower section or strip 20, the bottom edge of which is straight and the top edge of which is cut upon the bias to fit the sections to which it is connected as by stitching 21. It is to 45 be noted in this respect that the apex of the bottom piece and the back piece and intermediate piece are all joined at a point under the armpit portion, to provide strength at this point for compression purposes. In 50 practice, the section 20 extends around the supporter immediately below the bust line and serves to keep the supporter from slipping upward thus permitting the bust supporting pockets to well support the bust.

55 The section 20 also serves to compress the fleshy rib parts of the body beneath the arms thereby providing a neat, trim appearance. Shoulder straps 17 connect the back sections with the bust pockets, stitching being employed for effecting such connection. The 60 rear sections of the supporter are detachably secured together along a substantially vertical line as by means of hooks and eyes, elastic strips 22 preferably being employed 65 in this connection as shown. One of the

sections 18 may be faced upon its inner side with tape 23 or the like to which is secured the strips of elastic 22. The free ends of the elastic strips have stitched thereto superimposed strips of tape 24—25 between 70 which strips are secured hooks 26. The inner face of the opposite section 18 has stitched thereupon a strip of tape 27 to which are secured eyes 28 for coöperative engagement with the hooks 26. Both hooks 75 and eyes as thus secured are located in a pocket and hidden from view. In wearing a low cut gown, the upper elastic strips may be left in unfastened position as the lower strip serves to provide a secure attachment. 80

The above described supporter is constructed as low as possible, particularly the back, so that the same may be worn by persons wearing décolleté gowns and by dancers. The front is relatively high to cover 85 the entire breast. When acrobatic dancing is indulged in, where entire freedom of the muscles is necessary, the shoulder straps may be made sufficiently yielding for the purpose. The sections 10—13—16, it will 90 be understood, form substantially conical pockets for bust reception and in this connection it will be observed that the lower sections support and form the bust along natural lines and the upper sections or tabs 95 16 serve to hold down and round out the bust and prevent agitation thereof when vigorous exercise, as dancing, is indulged in. As the bust is thus rounded out and maintained in graceful lines, so the fatty 100 rib portions beneath the arm are likewise maintained in symmetrical contour by the lower section 20 which compresses at the point hereinbefore referred to as being strengthened beneath an armpit portion. 105

As thus constructed, the straight of the assembled section of fabric is in two general directions. The straight of sections 10—13—18 and 20 is drawn rearward in a substantially horizontal manner as the two rear sections are secured together thus raising the bust and preventing sagging thereof. With the rear sections secured together and shoulder straps in position, it will be noted that the pull of the straight of sections 16 is upward from the bust pocket centers, thus serving to hold down and round out the bust. Thus all the natural, graceful curves of youth may be conserved and certain objectionable features which are prevalent in 120 modern dancing eliminated. The supporter may also be used with good results by mothers after childbirth by constructing same as at 30 in Fig. 4. It may likewise be worn with good results by mothers at this period when the breast is less firm than usual.

It will now be apparent that I have devised a novel and useful construction which embodies the features of advantage enumerated as desirable in the statement of the in- 130

vention and the above description and while I have in the present instance shown and described the preferred embodiment thereof of which has been found in practice to give 5 satisfactory and reliable results, it is to be understood that the same is susceptible of modification in various particulars without departing from the spirit or scope of the invention or sacrificing any of its advantages.

What I claim is:

1. An article of the character stated embracing an enveloping support made up of a multiplicity of attached sections of textile material to form a smooth, close fitting unitary structure, the back of which is open and is relatively low cut and the front of which is closed and is relatively high cut and is provided with substantially conical shaped bust pockets each formed of lower sections attached along a substantially vertical seam and a single upper section forming a tab secured to said lower sections along a downwardly curved seam, shoulder straps connecting said tabs with the back of the article and elastic means adjustably connecting the parts of the open back.
2. An article of the character stated embracing a closed front portion and an open back portion, said parts consisting of a series of attached pieces of soft inelastic material to provide a unitary structure with no interruption of garment continuity, the pieces of the front section being formed to provide 35 spaced substantially conical bust pockets, said article having attached to its lower edge throughout its extent a strip of inelastic material, said strip being arranged at such an elevation that it extends around the body 40 immediately below the bust line, shoulder straps connecting said pockets and back

portions and means for detachably connecting the back portions along a vertical central line, the straight of the material of said combined parts being such that in position upon the person the shoulder straps serve to pull upwardly the tops of said pockets and the pull or draw exerted upon the remainder of the article is in a substantially horizontal direction toward the back thereof.

3. An article of the character stated embracing an enveloping support made up of a multiplicity of attached sections of textile material to form a smooth, close fitting, unitary structure, the back of which is open and is relatively low cut and the front of which is closed and is relatively high cut and is provided with substantially conical shaped bust pockets each formed of a pair of lower sections attached along a substantially vertical seam and a single upper section forming a tab secured to said lower sections along a downwardly curved seam, one section of each of said pair of lower sections being extended rearwardly to a point beneath the arm-pits, a rear section connected along a substantially vertical seam to each rearwardly extended section, the bottom edges of said lower and rear sections forming a continuous, irregular line, a bottom piece having a straight lower edge secured to said sections by a seam following said irregular line and elastic means for detachably connecting the rear sections of the supporter together.

In testimony whereof, I have hereunto signed by name.

ETHEL M. QUIRK.
